No. 3

Fig. 1.

Fig. 2.

Dec. 189

Amos Paul of South New Market N.H.
Letters Patent No 289. Dated June 11, 1850

The Schedule referred to in these Letters Patent and making part of the same.

To all Persons to whom these Presents shall come:

Be it known that I

Amos Paul of South New Market in the County of Rockingham and State of New Hampshire, have invented or produced a new and useful design for the side, front and base plates of a Cooking Stove, and I do hereby declare that the said new design is fully described and represented in the following specification and accompanying drawings, to which reference is hereinafter made,

Of the drawings Fig. 1, is an elevation of the side plate aforesaid, and fig. 2, is a section of the same taken in the plane of the line A-B fig. 1. Fig. 3, is an elevation of the front plate, and fig. 4, is an elevation of the edge of the base plate, while fig. 5, is a sectional view of the same.

My new design consists, firstly, in ornamenting the oven door A, the rectangular panel B, over the said door, the fire chamber door C and the ash pit door D, each with a bull's eye a, a &c. in alto relief with radial notches from the centre to the circumference from which circumference radiate in every direction, the radial ribs b-c, b-c &c. which are made alternately concave and convex, as shown in fig. 2, each door and panel being surrounded by an ogee moulding d d d d, and the whole plate having around it a neat ribbed moulding e e e e.

In the second place, my design consists in moulding the two doors E & F of the front plate, with bull's eyes h h, and radial concave and convex ribs i-k &c. and moulding l l l l precisely similar to the doors C & D on the side and forming a similarly ornamented panel G-H on each side of the front plate, and an elongated plain panel I I over said doors, and lastly, my design consists in ornamenting the moulding around the hearth plate with the row of pointed leaves m, m, m, &c. fig. 4, and the series of alternate notches and ridges n, o, n, o &c.

Having thus described my new design, I shall state my claim as follows. —

2

289

Des. 289

What I claim as my invention or production and desire to have secured to me by Letters Patent is, the combination of the bull's eyes in alto relief, (having radial notches as described) and of alternating concave & convex radial ribs & surrounding mouldings, on the several doors and panels of the front and side plates, and the row of pointed leaves m. m. and of alternate notches and ridges n. o. &c. on the moulding of the hearth plate, all as herein above set forth and represented in the drawings.

Witnesses.

Ezra Lincoln.
